UNITED STATES PATENT OFFICE.

JOHN DEELEY AND JAMES S. EDGE, JR., OF YARDLEY, ENGLAND.

IMPROVEMENT IN BREECH-LOADING FIRE-ARMS.

Specification forming part of Letters Patent No. 151,478, dated June 2, 1874; application filed May 1, 1874.

To all whom it may concern:

Be it known that we, JOHN DEELEY, of Yardley, in the county of Worcester, England, manager of works, and JAMES SIMEON EDGE, the younger, of Yardley aforesaid, mechanical engineer, have invented certain Improvements in Breech-Loading Small-Arms, of which the following is a specification:

Our invention has reference to breech-loading small-arms called "vertically-sliding-block guns;" and consists of the arrangements hereinafter described, and illustrated in the accompanying drawings, of mechanism for raising and lowering the block, for cocking the striker or hammer, and for extracting the empty case of the cartridge from the barrels of the said guns.

Figure 1 is a longitudinal vertical section of the breech end of a sliding-block gun, the parts of which are constructed and arranged according to our invention. Fig. 2 represents the same after the trigger-guard has been depressed and the breech opened and the gun cocked. Fig. 3 represents the opposite side of the gun to that represented in Fig. 2, and shows the arrangement for operating the extractor. Fig. 4 represents the breech-block and parts connected with it detached from the body of the gun.

a is the body of the gun, in which the vertical sliding block *b* works to open and close the breech. The said block *b* is hollow, and contains the discharge and cocking mechanism. *c* is the trigger-guard, turning on a joint at *d* on the body *a*, so that the said trigger-guard may be raised to, or lowered from, the said body. The said trigger-guard *c* is furnished with a thumb-plate, *c'*, for operating it, and is connected to the sliding block *b* by the hooked arm *e* taking into a recess, *b'*, in the side of the sliding block, so that when the trigger-guard is raised or lowered the said block *b* is raised or lowered. *f* is the striker, sliding horizontally in the block, and urged forward by the coiled spring *g*. *h* is the tumbler of the gun, turning on the center *h'* at the front of the sliding block *b*. At the front of the said tumbler is a projecting arm, *h''*, the said arm bearing upon the knuckle *d'* of the joint of the trigger-guard *c*. By means of the said projecting arm *h''* the tumbler *h* is cocked

on depressing the block *b*, as hereinafter explained. On the head or upper side of the tumbler *h* is another projection, *h'*, which, on the lowering of the trigger-guard and block, withdraws the striker *f* by bearing against the inclined shoulder *f'* on the said striker. When the tumbler *h* has been brought to the full-cocked position its further motion is arrested by the stop *h''* coming against the body of the gun. *i* is the trigger, turning on the center *i'*, and *i'* is the trigger-spring. *i''* is the sear, which engages with the bent or notch in the tumbler *h*, and holds it at full-cock. *k* *k'* is the extractor, consisting of a lever situated and working in the side of the breech-body *a*. (See Fig. 3.) The lower arm *k'* of the extractor is curved, and above it is a hooked arm, *l*, on the trigger-guard *c*. After the breech has been completely opened by the descent of the block *b*, the said hooked arm *l*, by acting on the arm *k'* of the extractor, gives motion in the proper direction to the upper or extracting arm *k*, and causes the latter to extract the empty cartridge-case from the barrel of the gun.

The action of the gun is as follows: When the gun has been discharged, the several parts occupy the respective positions represented in Fig. 1. In order to open the breech to reload the gun, the trigger-guard *c* is lowered from the body *a*, as illustrated in Figs. 2 and 3. The first action of the trigger-guard *c* causes its knuckle *d'* to act upon the projecting arm *h''* of the tumbler, and turn the said tumbler on its center *h'*. By this motion the projection *h'* on the upper part of the tumbler bears against the inclined shoulder *f'* on the striker *f*, and withdraws the nose of the striker into the block *b*, and permits the said block to descend. On the continued motion of the trigger-guard *c*, the bent in the tumbler *h* is brought opposite the sear *i''*, and the said sear engages therewith and cocks the gun—that is, the striker *f*, by the action of the parts *f'* *h'*, has been pushed back and its spring compressed, the striker being held in its withdrawn position by the tumbler *h*. During the cocking of the gun, the block *b* has been lowered in the body by the hooked arm *e* on the trigger-guard, and the breech opened, as illustrated in Fig. 2. As soon as the block *b* has been lowered sufficiently to open the

breech, the hook *l* on the opposite side of the trigger-guard operates the extractor *k* *k*², and causes the empty cartridge-case to be extracted from the barrel. Thus, by the lowering of the trigger-guard *c*, the striker *f* is withdrawn and cocked and held in a cocked position, the breech opened, and the empty cartridge-case extracted. After the introduction of a fresh cartridge into the barrel, the trigger-guard *c* is lifted to the body, when the sliding block *b* is again raised in the body *a* and the breech closed, and the gun is ready for discharge. On pulling the trigger *i* the sear *i*² is liberated from the bent in the tumbler *h*, and the striker *f* is advanced by its coiled spring, and, striking the cartridge, discharges the gun, as illustrated in Fig. 1. The trigger-guard *c* may be held in its raised position under the body *a* by a snap-fastening.

Fig. 5 represents a section, and Fig. 6 an end elevation, of a modification for connecting the jointed trigger-guard to the sliding block and for cocking the hammer. Fig. 7 is a side elevation of the block and trigger-guard detached from the body of the gun.

In this modification the trigger-guard *c* *c*² is furnished with knuckles *c*³ *c*³, which are made to embrace the hammer *m*, and are jointed to the sliding block *b* by the center-pin *m*³, on which the hammer *m* turns. The guard-lever *c* *c*² is jointed to the body *a* of the gun by the joint-pin *c*⁴ and slot *c*⁵, the said slot *c*⁵ permitting the said trigger-guard to have a slight play upon the said pin *c*⁴. The projecting part *m*⁴ at the front of the hammer *m* is shorter than the corresponding part in the arrangements before described. When the trigger-guard *c* *c*² is first depressed it turns on the center *m*³. The part *c*⁷ of the said trigger-guard is thereby raised, and, by bearing against the projection *m*⁴ of the hammer *m*, lifts and partly cocks the said hammer. This raising of the short arm of the trigger-guard causes the bottom of the slot *c*⁵ to engage with the joint-pin *c*⁴, and the said joint-pin now constitutes the center on which the trigger-guard turns. As

the trigger-guard is further depressed the block *b* is lowered in the body and the gun is opened for charging, the hammer *m* being fully cocked by the engaging of the sear *i*² with the bent in the said hammer.

Having explained the nature of our invention, and the manner in which the same is to be performed, we wish it to be understood that we claim as our invention of improvements in those kinds of breech-loading small-arms called "vertically-sliding-block guns,"—

1. The combination, with the vertically-sliding breech-block and the jointed lever for raising and lowering said block, of the hammer or hammer-tumbler, pivoted in and carried by said block, and operated by the said lever to effect the cocking of the piece during the vertical descent of the block, as herein shown and set forth.

2. The jointed trigger-guard connected with the body of the gun by a loose joint, and with the sliding breech-block by the pin or center on which the hammer turns, substantially as described, and shown in Figs. 6 and 7 of the drawings.

3. The combination, with the vertically-sliding breech-block and hammer pivoted to and carried by the same, of the trigger-guard jointed to the body of the gun by a joint-pin, *c*⁴, and slot *c*⁵, connected with the breech-block by knuckles *c*³, mounted and working on the center-pin or axis of the hammer, and provided with a knuckle or shoulder, *c*⁷, to operate against the projection *m*⁴ of the hammer, substantially as described, and shown in Figs. 5 and 6 of the drawings.

4. In combination with the extracting-lever *k*, the jointed trigger-guard having hook *l*, adapted to operate on the lower arm of said extracting-lever, as shown and set forth.
